(57) **CLAIM**

The ornamental design of a skid jettter machine, as shown and described.

DESCRIPTION

FIG. 1 is a perspective view of the skid jettter machine.

FIG. 2 is a front elevation of the skid jettter machine.

FIG. 3 is a rear elevation of the skid jettter machine.

FIG. 4 is a left-side elevation of the skid jettter machine.

FIG. 5 is a right-side elevation of the skid jettter machine.

FIG. 6 is a top plan view of the skid jettter machine; and,

FIG. 7 is a bottom plan view of the skid jettter machine.

The broken lines in the drawings depict portions of the skid jettter machine that form no part of the claimed design.
